APPARATUS FOR THE ERECTION OF
CONCRETE BUILDINGS

Benjamin Miller, Bronx, N. Y.

Application September 26, 1946, Serial No. 699,463

6 Claims. (Cl. 25—1)

1

This invention relates to concrete.

An object of the invention is to provide a form for pouring concrete in a horizontal plane, and having means for placing the finished slab in its desired position.

Another object of the invention is to provide a concrete pouring form which is so arranged as to be supported in a horizontal plane for pouring a slab, and is so arranged as to be turned out of a horizontal plane for emplacing the slab in a vertical final position without the need for hoisting.

A further object of the invention is to provide a form for pouring concrete slabs right on the building site, and in a horizontal plane, the form being supported at a point spaced from its center of gravity so as to be normally biased toward tilting out of the horizontal plane, and being further provided with restraining means for holding the form horizontally until the concrete sets and then for allowing it to gradually tilt into a vertical plane.

Still another object of the invention is to provide an apparatus for casting concrete slabs and emplacing them without the use of hoists or other similar apparatus.

Another object of the invention is to provide a concrete slab casting device by means of which the finished slabs may, without being transported, be placed in a final position in a wall or floor of a building, and which device is characterized by simplicity of design, ease and low cost of operation, and effectiveness for the purpose intended.

Other objects and advantages of the invention will become apparent from the following description of a preferred embodiment thereof as illustrated in the accompanying drawings, and in which

Figure 1 is a side elevation of my improved concrete slab forming and emplacing device.

Figure 2 is a fragmentary elevation of a portion of the device shown in Figure 1, as seen on line 2—2 of that view, and

Figure 3 is a side elevation similar to that of Figure 1, but showing a modified form of the invention.

In building construction employing preformed concrete slabs for the floors and walls, it is of considerable advantage for the slabs to be formed right on the site of the building, particularly in view of the saving in cost of transportation and handling. However, even when they are formed right at the job location, there is still considerable handling and movement of

2

the slabs before they are emplaced in their final positions. The present invention discloses a device by means of which the slabs may be preformed and then set into their final positions in the walls or floors with a minimum of handling, and substantially no transportation of the finished slabs at all.

Reference may now be had to the drawings, in which like reference characters denote similar parts throughout the several views. As illustrated in Figures 1 and 2, I provide a base member 10 which may be of wood or other material and is preferably of fairly substantial construction inasmuch as the entire device together with the cast concrete slab are supported thereby. The base 10 extends sufficiently to the right in Figure 1, to allow counterweights to be placed thereon if necessary, to avoid tipping. An upright tubular post 12 is secured at its lower end 14 by welding or other suitable means to a flange member 16 securely carried upon the upper surface 18 of the base member 10.

A second tubular member 20 has its lower end portion 22 bent vertically as shown, from the inclined main portion 24 of the member 20, and has its upper end portion 26 also bent at an angle from the main portion 24. The lower end 22 is securely inserted and preferably welded into a flange 28 which is bolted to the upper surface 18 of the base 10 in a manner similar to that of flange 16. The upper end 30 of the upright support post 12 is securely attached to the upper end 26 of the tubular member 20, preferably by welding as shown.

A lower bracket 32 has a tubular body portion 34 encircling the support post 12 and slideable upwards and downwards upon the post. A pair of side plates 36 and 38 are welded to opposite sides of the tubular body portion 34 and are connected along their upper edges 40 by means of a shelf 42, shown best in Figure 2. The tubular post 12 has a number of axially aligned pairs of lateral apertures 44 for the reception of positioning bolts 46 which are inserted through matching holes in opposite sides of the bracket 32 when the holes are in registry, there being sufficient apertures to permit positioning the lower bracket at any one of a number of possible locations along the length of the post 12.

An upper bracket 48, also has a tubular body portion 50 which encircles the post 12 in the same fashion as the corresponding part of the lower bracket 32, being similarly movable longitudinally of the post. The upper bracket has a pair of side plates 52 and 54 which are welded

to opposite sides of the tubular body portion 50 and they are connected along their upper edges 56 by means of a shelf 58, shown best in Figure 2. The upper bracket 48 is supportable in any desired location along the post 12 by means of a positioning bolt 60 which is inserted through any appropriate pair of apertures 44 in the post 12, the bracket resting upon the bolt.

A lateral plate 62 is welded to the upper surface of the shelf 58, the plate 62 being longer than the shelf and thus extending outward to either side thereof as best shown in Figure 2. Cylindrical bearings 64 and 66 are supported upon the plate 62 with their axes horizontal and in alignment, the bearings being preferably welded to the plate at 68 along a portion of their outer surfaces.

The bearings 64 and 66 are adapted for the reception and pivotal support of a lateral shaft or rod 70 which extends through both bearings as seen in Figures 1 and 2. The shaft 70 extends through apertures formed in the lower portion 72 of a concrete slab casting form 74 which has a platform indicated by the line 76 with upstanding side and end walls 78 and 80 extending above the platform to form an upwardly open recess into which the concrete may be poured and allowed to solidify in slab form, as defined by the shape of the recess.

It is to be noted that the support shaft 70 extends through apertures in the casting form 74, which are so disposed as to be spaced from and to the right of the center of gravity of the casting form and its slab, the result being that the form and slab are normally gravity biased to tip over or pivot about the shaft 70 to the left as seen in Figure 1, that is, in a counterclockwise direction. To prevent such tipping, and to retain the casting form in a horizontal position as shown in full lines in Figure 1, a tie rope or cable 82 has one end 84 securely tied to a stationary eye member 86 which is fastened to the base 10, and has its other end 88 securely tied to an eye-bolt 90 projecting out of the side of the casting form as shown in Figure 1, substantially precise leveling being accomplished by means of the turn buckle 92 which is interposed in the cable 82 intermediate its ends.

Where the casting form is of any substantial width, that is, perpendicular to the plane of the paper, as seen in Figure 1, it is apparent that the support shaft 70 will be of substantial length in order to support the casting form, and that more than one set of supports for the shaft 70 will be employed, to support it at several points along its length.

In use, with the casting form in horizontal position as shown in Figure 1, the concrete is poured into the recess in the form and allowed to harden. Then, if the slab is to be part of a vertical wall, it will be necessary to emplace the slab in a vertical position, either upon a foundation, or upon other slabs, such as in the position indicated by the dotted lines at 94. This may be accomplished by merely turning the central portion of the turnbuckle 92 to lengthen the cable 82, thereby allowing the gravity biased concrete form to tilt or pivot gradually to the left or counterclockwise as is seen in Figure 1, until it is finally in a vertical position and to the left of the up-right support post 12.

To allow the slab in the form to be lowered into position, which may be with its lower end 96 resting upon the ground surface 98, a jack 100 is provided, the base 102 of the jack resting upon

the lower shelf 42 and the upper end of the vertically movable jack plunger 104 being moved upwards beneath the upper shelf 58 so as to elevate the upper shelf slightly, permitting the bolt 60 to be withdrawn whereupon the jack supports the upper bracket, the shaft 70 and the entire casting form and slab therein.

The jack plunger 104 is then lowered, carrying with it the upper bracket, shaft 70 and casting form and slab, and the lowering of the plunger is continued until the slab is in the desired position. Suitable means, not shown, will necessarily be employed for opening out the form wall 80 and for retaining the slab within the form as it is being lowered into position. It will also be apparent that the process may be performed automatically without turning the central portion of the turnbuckle and without changing the length of the cable 82 at all. Thus, the hardened slab and its form may be lowered by means of the jack 100, and the bolt 60 having been first removed as already described. Then continued lowering of the jack plunger will cause the angle between the horizontal base 10 and the cable 82 to be progressively decreased, causing the upper end 88 of the cable to swing to the left under the influence of the thus unbalanced weight of the form and slab, and allowing the slab and form to pivot gradually and automatically about the shaft 70 to vertical position shown in dotted lines, from which it can be lowered into final position as desired.

A modified form of the invention is shown in Figure 3, and this has particular utility in connection with the handling of concrete slabs which are to form sections of a floor, that is, which are to be installed in horizontal position. The form shown has parts which are similar to those shown in Figures 1 and 2, including a base such as at 10, and tubular supports 12 and 20. It also has a bracket 106 similar to lower bracket 32, and an upper bracket 108 similar to upper bracket 48, the upper bracket being movable upon an extension tube 110 protruding upwardly out of the upper end of the support 12 and supported therein, the tube 110 having apertures 112.

The upper bracket 108 is supported by a bolt 114 similarly to bolt 60 in Figure 1, and similarly supports the shaft 70 which pivotally supports the casting form 74. Tie ropes or cables 116 and 118 are tied at their upper ends to eyebolts 120 protruding out of the side walls of the casting form, and are tied at their lower ends to the eye number 122 attached to post 112, thus retaining the casting form in horizontal position. After the concrete slab has set, and hardened, a jack 100 supported on the lower bracket 106 similarly to that shown in Figures 1 and 2 for bracket 32, has its plunger moved upwards to elevate the upper bracket 108 above the bolt 114, the upward movement of the jack being continued until the form and slab are at the proper height for emplacement, whereupon the form may in any suitable manner be sufficiently removed to allow the slab to be emplaced.

Any suitable well known type of anchor bolts may be employed to prevent the concrete form from sliding off the form when tilting the same, as described in connection with Figs. 1 and 2 of my invention.

It is also noted that in the Figs. 1 and 2 form, in accordance with my invention, when the slab 94 has been tilted to vertical position, as shown in dotted lines, suitable concrete blocking B of any well known type and method may be used under the bottom edge 96.

Although I have described a preferred embodiment of my invention in specific terms, it is to be understood that various changes may be made in size, shape, materials and arrangement without departing from the spirit and scope of the invention as claimed.

I claim:

1. A concrete construction device comprising a frame, upper bracket means carried by said frame, lateral shaft means carried by said upper bracket means, a concrete slab form pivotally carried upon said shaft means, said form being normally horizontal and adapted for being filled with concrete which upon hardening therein forms a slab, means for maintaining said form in horizontal position, lower bracket means carried by said frame, lifting means carried by said lower bracket means and operative to elevate and lower said upper bracket means, whereby upon lowering of said lifting means, said form and slab are pivotally moved into a vertical plane, and upon further lowering thereof slab is lowered into a final position upon a portion of a building or the like.

2. A concrete construction device comprising a frame, upper bracket means carried by said frame, a lateral shaft pivotally carried by said upper bracket means, a concrete slab form pivotally carried along a line lying to one side of its center of gravity upon said shaft, said form being normally horizontal and adapted for being filled with fluid concrete mixture which upon hardening therein forms a slab, cable means attached at one end to said frame and at the other end to said form at a point on the other side of its center of gravity from said pivotal support whereby said form is normally held in horizontal position and restrained against pivotal movement, lower bracket means carried below said upper bracket means upon said frame, jack means supportable upon said lower bracket means and having its movable plunger disposed below the upper bracket, whereby upon upward motion of said plunger said upper bracket means may be elevated and said upper bracket supported by said plunger and released from direct support by said frame, and whereby upon downward motion of said plunger said upper bracket means is lowered thereby automatically and gradually releasing the restraint imposed by said cable means against pivotal motion of the form and allowing the form and slab automatically to pivot to a vertical plane, whereby upon continued down-

ward motion of said plunger said slab may be lowered into final position upon a portion of a building.

3. A concrete construction device comprising a frame, an upward extension carried by said frame, lower bracket means carried by said frame, upper bracket means carried by said extension, a lateral shaft pivotally carried by said upper bracket means, a concrete form pivotally carried upon said upper bracket, cable means for maintaining said form in normally horizontal position whereby concrete mix may be poured into the form and allowed to harden to form a slab, and elevating means carried by said lower bracket means and operative upon said upper bracket means whereby upon operation of said elevating means said upper bracket means is elevated thus elevating said form and slab into a final horizontal position upon a portion of a building or the like.

4. A concrete construction device according to claim 1 in which the said upper and lower bracket means are mounted for relative movement along the frame.

5. A concrete construction device according to claim 2 in which said frame comprises a tubular upright member, and in which said upper and lower bracket means each include a tubular portion through which said tubular upright member passes.

6. A concrete construction device according to claim 5 in which openings are provided in said tubular upright member spaced along the length thereof and in which corresponding openings are provided in said tubular portions of said upper and lower bracket means, and in which the position of said upper and lower bracket means may be selectively maintained on said tubular upright member by inserting a holding pin in one of said openings in said tubular upright member.
